SLIDE HEAD TOOL

Howard W. Dase, Strongsville, Ohio, assignor to The Warner & Swasey Company, Cleveland, Ohio, a corporation of Ohio

Filed Aug. 30, 1967, Ser. No. 8,431

Term of patent 14 years

(Cl. D54—6)

FIG. 3

FIG. 4

FIG. 5

FIG. 6

FIG. 1 is a front elevational view of a slide head tool embodying my new design;

FIG. 2 is a right side elevational view of the slide head tool of FIG. 1;

FIG. 3 is a bottom plan view of the slide head tool of FIG. 1;

FIG. 4 is a left side elevational view of the slide head tool shown in FIG. 1;

FIG. 5 is a top plan view of the slide head tool shown in FIG. 1; and

FIG. 6 is a rear elevational view of the slide head tool of FIG. 1.

What I claim is:

The ornamental design for a slide head tool, substantially as shown and described.
